[57] CLAIM

The ornamental design for kitchen knife, as shown.

DESCRIPTION

FIG. 1 is a front elevational view of a kitchen knife showing my new design;

FIG. 2 is a rear elevational view thereof;

FIG. 3 is a cross section view taken along lines 3—3 on FIG. 4;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view of a second embodiment of my new design of FIGS. 1-7;

FIG. 9 is a rear elevational view thereof;

FIG. 10 is a cross section view taken along line 10—10 on FIG. 11;

FIG. 11 is a top plan view thereof;

FIG. 12 is a bottom plan view thereof;

FIG. 13 is a left side elevational view thereof; and,

FIG. 14 is a right side elevational view thereof.
